UNITED STATES PATENT OFFICE.

HARRY LYON, OF BROCKTON, MASSACHUSETTS, ASSIGNOR TO JOHN A. BARBOUR AND PERLEY E. BARBOUR, FIRM DOING BUSINESS AS BROCKTON RAND COMPANY, OF BROCKTON, MASSACHUSETTS.

WELTING FOR SEWED BOOTS AND SHOES.

1,054,225.

Specification of Letters Patent. Patented Feb. 25, 1913.

Application filed June 21, 1912. Serial No. 705,027.

To all whom it may concern:

Be it known that I, HARRY LYON, a citizen of the United States, and a resident of Brockton, in the county of Plymouth and 5 State of Massachusetts, have invented certain new and useful Improvements in Welting for Sewed Boots and Shoes, of which the following is a specification.

This invention relates to leather welting used in sewed boots and shoes and particularly Goodyear and McKay sewed work. In 10 welting of this character, the grain surface of the leather forms the outer or exposed surface of the welt, this surface being more firm and dense than the opposite or flesh surface and capable of receiving a desirable finish. The firmness and density of the grain surface renders the welt less flexible and pliable than is desirable, particularly 15 at points where the welt is bent edgewise, as at the toe portion of the boot or shoe.

My invention has for its object, first, to increase the flexibility of the grain surface of leather welting, and secondly, to facilitate 20 the operation of ornamenting the grain surface by the formation of transverse grooves therein by a rotary indenting tool which when rolled over the exposed surface of the welt forms a series of parallel indentations 25 therein.

The invention consists in the improvements which I will now proceed to describe and claim.

Of the accompanying drawings:—Figure 1 30 represents a perspective view of a welt strip embodying my invention. Fig. 2 represents an edge view showing the strip bent sideways. Fig. 3 represents a side view showing the strip bent edgewise. Fig. 4 represents an edge view showing the manner of ornamenting the welt after its incorporation into 35 a boot or shoe.

The same reference characters indicate the same parts in all the figures.

In carrying out my invention I form in 40 the grain surface of a leather welt strip *a* a series of transverse grooves *b* which are formed by cutting out narrow portions of the grain surface, the grooves extending

continuously from edge to edge of the strip 50 and leaving narrow portions of the grain surface in the form of transverse ridges between the grooves. The grooves *b* may be formed by any suitable cutting or gouging tool which is adapted to remove narrow 55 pieces of the material, or to otherwise form the grooves *b* by removing the material from the grooves.

A welt strip having portions of its grain surface removed to form transverse grooves, 60 as shown, is rendered more flexible than an ordinary welt strip, the grain surface of which is continuous, the strip being adapted to be freely bent sidewise, as indicated by Fig. 2, to adapt its sides to the curvatures 65 of the outer sole, and edgewise, as shown by Fig. 3, to adapt its edges to abrupt curves such as those at the curved toe portion of the outer sole.

The grooves are preferably proportioned 70 and spaced to correspond to the grooves or indentations usually formed in the exposed side of a welt by an indenting tool after the welt has been secured to the outer sole, the indenting tool being usually a ribbed or 75 fluted roll *c* which is in rolling contact with the exposed side of the welt. Such tool has heretofore been employed to force portions of the grain side of the welt inwardly and thus form indentations, no portions of the 80 grain surface being removed.

The usual indenting operation requires several passages of the indenting tool over the welt to form indentations of the desired depth in the grain surface. By employing 85 an indenting tool *c* the ribs of which are adapted to coincide with the grooves *b* I am able to insure the formation of grooves of the desired depth by a single passage of the indenting tool over the welt, the ribs of the 90 indenting tool entering the grooves *b* and compressing the material constituting the bottoms of said grooves so that they are desirably dense and firm and correspond in density with the intermediate portions of 95 the grain surface between the grooves. The exposed side of the welt therefore, does not present a porous or fibrous appearance, said

side being composed in part of the original grain surface and in part of the compact bottoms of the grooves.

I claim:—

- 5 A leather welt strip having one of its sides formed by the grain surface of the leather, and provided with transverse grooves extending from edge to edge and formed by removing narrow portions of the grain sur-

face, the grooves being separated by narrow intermediate grain surface portions.

In testimony whereof I have affixed my signature, in presence of two witnesses.

HARRY LYON.
